AIR CONDITIONING APPARATUS

Arthur H. Eberhart, Springfield, Mass., assignor to Westinghouse Electric & Manufacturing Company, East Pittsburgh, Pa., a corporation of Pennsylvania

Application March 2, 1940, Serial No. 321,875

10 Claims. (Cl. 62—129)

This invention relates to air conditioning apparatus and more especially to an air-cooled room cooler.

Air-cooled room coolers are rather bulky because of the large air ducts required in such apparatus. It is accordingly an object of this invention to provide a more compact room cooler.

Another object of the invention is to provide a simplified room cooler which is economical to construct.

A still further object of the invention is to provide a simplified manual control for actuating the regulating valves of the air ducts.

These and other objects are effected by my invention as will be apparent from the following description and claims taken in connection with the accompanying drawings, forming a part of this application, in which:

Fig. 1 is a view in perspective of the room cooler of this invention, as seen from the front, parts of the cabinet being broken away;

Fig. 2 is another view in perspective of the room cooler as seen from the rear, parts of the window ducts being broken away;

Fig. 3 is a view in perspective of the window duct structure with parts broken away;

Fig. 4 is a vertical section of the room cooler installed in a window, the section being taken on the line IV—IV of Fig. 6 but with the motor-compressor unit removed;

Fig. 5 is an elevation of the side of the room cooler with parts broken away to show the path of the air which enters the room;

Fig. 6 is a horizontal section of the room cooler taken on the line VI—VI of Fig. 5 but with parts of the motor-compressor unit shown in full;

Figs. 7, 8 and 9 are vertical sections of the window duct structure taken on the line VII—VII of Fig. 6, Fig. 7 showing the initial engagement of the operating strip with the contact finger, Fig. 8 showing the initial lift of the room air exhaust valve, and Fig. 9 showing the room air exhaust valve in its fully open position; and,

Fig. 10 is an elevation of the side of the room cooler showing the window-connecting duct in its lowermost and in its uppermost position.

Referring now to the drawings in detail, the reference numeral 10 represents a cabinet for housing the room cooler of this invention. A removable duct structure 11 is secured to the back of the cabinet 10 and is adapted to communicate with the air exterior of the room being cooled, preferably through an open window

12. The window duct structure 11 is adjustable as to height with respect to the cabinet 10 to provide for connection to windows of varying window sill heights.

5 The cabinet 10 is divided by a horizontal wall 13 into an upper cooling compartment 14 and a lower compartment. The horizontal wall 13 is supported by a vertical wall 15 and by two end supports 16, which wall and supports are secured at their lower ends to a base plate 17. The vertical wall 15 divides the lower compartment into two chambers which will hereinafter be referred to as the filter compartment 18 and the apparatus compartment 19, respectively.

10 The window duct structure 11 is divided by a vertical partition 21 into two passageways, one serving as an air inlet duct 22 and the other as an air exhaust duct 23 for the cabinet 10. These ducts communicate through openings 24, 25 and 30 in the back wall of the cabinet 10 with the interior thereof.

15 The passages traversed by the air which enters the room to be cooled hereinafter referred to as the room, and the apparatus for filtering, circulating, and cooling this air will now be described. The cooled air which enters the room may be taken from the room itself thereby providing for a recirculation of the room air or may be taken from the outside through the window inlet duct. Two air inlets are, accordingly, provided for this air, one being an opening 26 located at the base of the rear wall of the cabinet 10 and the other being an opening 24 located a spaced distance above the opening 26 and 20 communicating with the window inlet duct 22.

25 A common closure slide 27 is provided for the two openings 24 and 26, which slide, in its upper position, covers the window duct opening 25 and uncovers the room air opening 26, and, in its lower position, covers the room air opening 24 and uncovers the window inlet duct opening 26. Intermediate positions of the closure slide 27 cover and uncover proportional areas of these openings 24 and 26 so that any mixture of room and outside air may be passed through the room cooler. The closure slide may be moved upwardly by means of a knob 28 secured thereto. The knob 28 projects through a slot 29 in the side of the cabinet 10.

30 The plate type air filter 32 comprising spun glass or the like is placed diagonally across the corners of the filtering compartment 18, dividing this compartment into an unfiltered air chamber 33 and a filtered air chamber 34. The air filter 32 is removable for replacement. The

upper portion of the filter compartment 18 above the air filter 32 is blocked off by a baffle 36 and is reserved for the electric control. A centrifugal fan 37 is located in the filtered air chamber 34 and communicates by means of a cloth duct 38 with the central rear portion of the cooling compartment 14. The fan 37 thus effects a circulation of air through either or both of the openings 24 and 26, through the unfiltered air chamber 33, through the air filter 32, through the filtered air chamber 34, through the fan 37 itself and through the cloth duct 38 into the air cooling compartment 14.

The cooling compartment 14 is divided by an evaporator or cooling unit 39 and baffles 41 into an air receiving chamber 42 and an air exhaust chamber 43. The evaporator 39 comprises a series of parallel spaced plates 44 through which a refrigerating tube 46 is passed back and forth. The air delivered by the blower to the air receiving chamber 42 passes between the parallel plates 44 of the evaporator 39, is cooled and passes to the air exhaust chamber 43. From this chamber 43 the cooled air issues through a grille 47 at the upper front edge of the cabinet 10 into the room.

The apparatus compartment 19 contains the necessary apparatus for supplying the evaporator 39 with liquid refrigerant and removing the vaporized refrigerant therefrom, which apparatus is well known in the art. It comprises a compressor 48, a motor 49 for driving the same and a condenser 51 for cooling and liquefying the vaporized refrigerant withdrawn from the evaporator 39. The condenser 51, like the evaporator 39, comprises a series of spaced parallel plates 52 and a tube 53 into which the compressed refrigerant vapor is pumped by the compressor 48.

The compressor 48 and the motor 49 for driving the same are contained in a fluid-tight metal casing 54, which casing is housed partly in the upper portion of the apparatus compartment 19 and partly in the air inlet duct 22 of the removable window duct structure 11. The part of the compressor 48 which projects into the removable window duct structure 11 comprises the cylinder 50 together with the removable cylinder head 55 and valves (not shown) so that these elements are accessible for repair without necessitating the removal of the compressor 48 from the cabinet 11.

The condenser 51 is housed in the upper portion of the apparatus compartment 19 adjacent the motor-compressor unit 48, 49 and is secured to the horizontal wall 13. The condenser 51 is enclosed in a metal sheath 56 which communicates at the rear with the air outlet duct 23 of the window duct structure 11 through the opening 30 in the rear wall of the cabinet 10. A metal bedplate 58 is secured to the lower portion of the sheath 56 of the condenser 51 and to the central portion of the vertical wall 15 and supports the motor-compressor unit 48, 49 through springs 59 interposed between the unit 48, 49 and the bedplate 58.

A motor 61 having an overhanging shaft 62 at both ends is secured in the lower portion of the apparatus compartment 19 substantially as shown in Fig. 1. One overhanging end of the shaft 62 projects through the vertical wall 15 into the filter compartment 18 and drives the rotor 63 of the centrifugal fan 37. The other end of the overhanging shaft 62 carries a rotor 64 of a double inlet blower 66, which blower 66 communicates with the lower 75

front portion of the condenser sheath 56. The rear of the cabinet is open adjacent the motor-compressor unit 48, 49 and communicates with the air inlet duct 22 of the window duct structure 11 so that an air passage is formed connecting the apparatus compartment 19 with the inlet duct 22. The apparatus compartment 19 also communicates with the double inlet blower 66 so that the blower 66 draws air through the air inlet duct 22 of the window duct structure 11 through the portion of the apparatus compartment 19 housing the motor-compressor unit 48, 49 and the motor 61 and forces the air through the condenser sheath 56 between the condenser plates 52 and out through the air exhaust duct 23 of the window duct structure 11, thereby cooling the condenser 51 to liquefy the refrigerant vapors therein.

The air entering the cabinet 10 from the window inlet duct 22 is not required to flow around the portions of the compressor 48 projecting into the window inlet duct 22 before entering the cabinet 10 because the inlet opening 25 of the cabinet surrounds and is partially above the projecting portions of the compressor 48. The compressor 48 therefore does not materially obstruct the flow of air through the window inlet duct 22. This placement of the motor-compressor unit 48, 49 economizes space as it permits the use of a cabinet of less depth than the length of the motor-compressor unit 48, 49.

A portion of the moisture of the air passing through the evaporator 39 will condense thereon. This moisture drips into a pan 67 located below the evaporator 39 and drains through a hose 68 into the rotor 64 of the blower 66. The moisture is atomized by the rotor 64 of the blower 66 and a portion thereof vaporizes. Another portion is blown against the warm condenser 51 where it is evaporated. A further portion of the atomized water is thrown against the casing of the blower 66. This water will run down and collect in a water pan 69 at the base of the blower casing, entering the pan 69 through holes in the lower portion of the casing of the blower 66. When the level of the water in the pan 69 and in the blower casing rises to adjacent the outer circumference of the rotor 64, it is atomized and entrained in the blower air stream.

The apparatus of this invention is also adapted for a rapid discharge of the air of the room through the window-outlet duct 23. An opening 71 is provided for this purpose in the rear wall of the window inlet duct 22. This opening 71 is normally closed by a flapper valve 72 pivoted to the inner wall of the duct immediately above the opening 71. The weight of the valve 72 ordinarily holds it in the closed position. A plate 73 is secured to the valve 72 and has a portion extending sidewardly thereof. The sidewardly-extending portion 74 carries a finger 76 which extends substantially at right angles with the valve plate 72 and inwardly in the air duct 22 when the valve 72 is closed.

The closure slide 77 is provided with an operating element comprising a strip of metal 77 secured to the lower edge of the closure slide 77. The strip 77 lies adjacent the slide for about four-fifths of its length and is then bent rearwardly to project into the air inlet duct 22 through the opening 24 of the cabinet 10. The upper end of the strip 77 is bent upwardly and is provided with a series of horizontal slots 78 which are adapted to engage with the finger 76 on the flapper valve 72.

When the slide 27 is in an upper position, as indicated in Fig. 7, the rearwardly-bent portion of the strip 17 strikes the upper edge of the opening 24, and on further upward movement of the slide 27, is forced rearwardly so that one of the slots 18 in the upper end of the strip 17 engages the finger 16. A further upward movement of the slide 27 pushes the finger 16 upwardly to the position shown in Fig. 8 to open the flapper valve 12. When this valve 12 is in its uppermost position, as shown in Fig. 9, it obstructs the inlet duct 22 and permits air to be withdrawn from the room through the opening 11 by the blower 66 and forced over the condenser 51 and out through the outlet duct 23 of the window-connecting duct 11. The elevation of the window duct structure 11 relative to the cabinet 10 determines which of the horizontal slots 18 in the operating strip 17 engages the finger 16. Changes in the elevation of the window-connecting duct 11 can thus be made without effecting the actuation of the valve 12.

The actuation of the various valves 27 and 12 is described and claimed in the inventor's pending application Serial No. 347,997, filed July 27, 1940 and assigned to the assignee of the present application.

The room cooler is provided with the usual switches, one switch 79 for supplying electrical energy to both the compressor motor 49 and the blower motor 61 and another switch 81 in series with the compressor motor 49, whereby the operations of this motor may be discontinued when mere circulation of the room air is desired or when the room air is being exhausted.

It will be apparent from the above that this invention provides a room cooler of compact design in which the motor-compressor unit is partially housed in the air intake duct. The invention also provides a novel control of the air valves of the room cooler.

While I have shown my invention in but one form, it will be obvious to those skilled in the art that it is not so limited, but is susceptible of various changes and modifications without departing from the spirit thereof, and I desire, therefore, that only such limitations shall be placed thereupon as are specifically set forth in the appended claims.

What I claim is:

1. In air conditioning apparatus, the combination of a cabinet, an evaporative cooling unit and a condenser therein, a duct having a portion extending exteriorly of said cabinet, said duct circulating air from exterior of said cabinet over said condenser, other devices associated with said air conditioning apparatus, said other devices comprising a compressor for withdrawing vaporized refrigerant from said evaporative cooling unit and passing said vapor to the condenser, and a motor for driving said compressor, some of said devices being located in the portion of the duct extending exteriorly of said cabinet.

2. In air conditioning apparatus, the combination of a cabinet, a compressor and a motor for driving the same, a fluid-tight casing surrounding said motor and compressor, a condenser and an evaporator in said cabinet, conduits interconnecting said compressor, condenser, and evaporator into a refrigerating unit, and a duct external of said cabinet for conducting cooling air to said condenser, said casing

being housed partially within said cabinet, the remainder extending into said duct.

3. In air conditioning apparatus, the combination of a cabinet, a duct removably secured to said cabinet for conducting air thereto, an evaporator and a condenser in said cabinet, a compressor, and a motor for driving the same, a fluid-tight casing surrounding said motor and compressor, said casing having a removable head, said casing being located in said cabinet and duct with the removable head in the removable duct, whereby on removing said duct the removable head of said casing may be removed without removing said casing from the cabinet.

4. In air conditioning apparatus, the combination of a cabinet, a removable duct secured to a side wall of said cabinet for conducting cooling air thereto, a condenser and an evaporator located in said cabinet, means in said cabinet for forcibly circulating air through said duct and over said condenser to cool the same, a compressor connected in operative relationship with said condenser and evaporator, a motor for driving the compressor, a fluid-tight casing surrounding said motor and compressor, said casing having a removable head, said casing being located partly in said cabinet and partly in said removable duct with said removable head in said removable duct, whereby on removing said duct the removable head of said casing may be removed without removing said casing from the cabinet.

5. In air conditioning apparatus, the combination of a cabinet, a duct removably secured to the exterior of said cabinet for circulating air therethrough, an evaporator and a condenser in said cabinet, a compressor in said duct, said compressor withdrawing vaporized refrigerant from the evaporator and passing it to the compressor, and a motor in said cabinet for driving said compressor.

6. In air conditioning apparatus, the combination of a cabinet, a condenser and an evaporator in said cabinet, a duct communicating with said cabinet and extending exteriorly thereof for circulating air exterior of said cabinet over said condenser, said compressor being located in said duct exterior of said cabinet and a motor within the cabinet for driving said compressor.

7. In a room cooler, the combination of a cooling unit, an air duct for circulating air over said cooling unit, said air duct having an entrance opening adapted to communicate with the air exterior of the room to be cooled and a second entrance opening adapted to communicate with the air in said room, valve means for each of said openings, a condenser, an air duct for circulating air over the condenser, said duct having an entrance opening adapted to communicate with the air exterior of the room to be cooled and a second entrance opening adapted to communicate with the air in said room, valve means for each of said openings, and a single control communicating with all of said valve means to adjust the same.

8. A self-contained air cooling unit comprising a wall structure providing a housing for the unit and including a window duct portion extending rearwardly from the upper rear portion of the unit; a horizontal shaft fan and motor unit in said housing adjacent the bottom thereof; an evaporator, a motor compressor unit and a condenser disposed in said housing directly above said fan motor unit and connected in re-

frigerant-flow relation; said fan and motor unit comprising a fan for effecting flow of air over the evaporator, a second fan for effecting flow of air over the condenser, and a motor disposed between and directly connected to both of said fans for driving the same; the wall structure forming a condenser air passage extending forwardly through the window duct portion, downwardly, through said second fan and through said condenser, upwardly, and rearwardly through the window duct portion, at least a portion of said motor compressor unit being disposed in vertical alignment with said downwardly-extending passage portion and in contact with the air flowing therethrough.

9. A self-contained air cooling unit comprising a wall structure providing a housing for the unit and including a window duct portion extending rearwardly from the upper rear portion of the unit; an evaporator, a motor compressor unit and a condenser disposed in said housing in the upper portion thereof and connected in refrigerant-flow relation; an evaporator fan effecting flow of air over the evaporator, a condenser fan effecting flow of air over the condenser, and a motor for driving both of said fans disposed in the lower portion of said housing; said evaporator being disposed above the evaporator fan, said motor compressor unit being disposed at least partly directly above said fan motor, and said condenser being disposed adjacent and at least partly directly above said condenser fan; the wall structure forming a condenser air passage extending forwardly through the window duct portion, downwardly

5 in vertical alignment with and in contact with at least a portion of the motor compressor unit, through said condenser fan, through said condenser, upwardly, and rearwardly through the window duct portion.

10 10. A self-contained air-cooling unit comprising a wall structure including a cabinet and including a window duct portion extending rearwardly from the upper rear portion of the cabinet, an evaporator disposed in the upper portion of the cabinet, the wall structure being formed with a condenser air passage extending forwardly through the window duct portion, downwardly in back of said evaporator, then forwardly, laterally and rearwardly below said evaporator, upwardly in back of the vaporator and then rearwardly through the window duct portion, a motor-compressor unit disposed in said passage directly below one of the portions of 15 the passage which extend vertically in back of the evaporator, a fan for effecting flow of outdoor air through said passage, a condenser disposed across said passage and cooled by the air flowing therethrough, said condenser being arranged below and at least partly beneath said evaporator, a fan disposed below said evaporator for effecting flow of air over the surfaces thereof, and a common drive motor for said fans, said fan motor and said motor-compressor unit being disposed directly above and below each other; the compressor, the condenser and the evaporator being connected in refrigerant flow relation.
